United States Patent Office.

WILLIAM J. SIMMONS, OF CHARITON, IOWA.

Letters Patent No. 89,799, dated May 4, 1869.

IMPROVED QUILTING-FRAME.

The Schedule referred to in these Letters Patent and making part of the same.

To whom it may concern:

Be it known that I, WILLIAM J. SIMMONS, of Chariton, Lucas county, Iowa, have invented a new and useful Quilting-Frame; and I hereby declare the following to be a full, clear, and exact description thereof, reference being had to the accompanying drawings, making part of this specification.

This invention relates to a frame upon which a quilt is stretched, and which, unlike the frames in ordinary use, requires no additional means of support, and which also has ready adjustability to any-sized quilt, and to the varying size of the quilt, as it is unrolled in the operation of quilting.

In the drawings—

Figure 1 is a perspective view of my improved quilting-frame.

Figure 2 is a section through two of the posts.

A are posts, upon which the frame is supported, and

B are side rails, which have free end-movement in mortises C, in the posts, when the winch-screws D are slackened out.

E are end rails, which have free end or rotary movement in the mortises F of the posts, when the aforesaid screws D are slackened out.

Attached along one edge of each end rail is a strip of cloth, e, of any preferred material, to which the ends of the quilt G are attached.

The winch-screws D pass downward from the centre of the post-tops, and through metallic nuts h, which are inserted in blocks H.

These blocks H fit snugly in mortises passing horizontally through the posts at their upper parts, the

said blocks forming a means for the introduction of the nuts to the position required.

The operation is as follows:

After the batting is enclosed, between the top and lining-sides of the quilt, the ends of the quilt are sewn fast to the strips e of the rails E. The ends may be then rolled around one or both of the said rails, to the extent desired, to bring all parts of the unrolled portion of the quilt within reach of the operators sitting outside the rails.

The rails B and E are then inserted in the mortises C and F, and the quilt being rendered sufficiently taut, the winch-screws are turned down, and their lower ends, impinging against the top of the rails E, cause them to press with sufficient force upon the rails B to hold the latter in place.

As the quilting is proceeded with, the rail, or rails, upon which the quilt is rolled, are loosened, by unturning the winches, and a portion of the quilt being unrolled therefrom, the posts are drawn along sufficiently to tighten the quilt, and the winches are then turned down, serving to render the whole rigid.

Having described my invention,

What I claim as new, and of my invention, is—
The described arrangement of mortised posts A C F, rails B E, and winches D, as and for the purpose stated.

In testimony of which invention, I hereunto set my hand.

WILLIAM J. SIMMONS.
